CLAIM

The ornamental design for a soda can lid, as shown and described.

DESCRIPTION

FIG. 1 is a perspective view of a soda can lid showing my new design;

FIG. 2 is a right side elevational view thereof;

FIG. 3 is a left side elevational view thereof;

FIG. 4 is a bottom plan view thereof;

FIG. 5 is a top plan view thereof; and,

FIG. 6 is a rear elevational view thereof.

The broken lines in the drawings depict environmental subject matter only and form no part of the claimed design.
